UNITED STATES PATENT OFFICE.

TETSUSHIRO NAKAMIGAWA, OF NEW YORK, N. Y.

LIQUID-GAGE.

1,247,317.

Specification of Letters Patent. Patented Nov. 20, 1917.

Application filed February 28, 1916. Serial No. 80,931.

To all whom it may concern:

Be it known that I, TETSUSHIRO NAKAMIGAWA, a subject of the Emperor of Japan, residing in the city, county, and State of 5 New York, have made a certain new and useful Invention in Liquid-Gage, of which the following is a specification.

This invention relates to liquid gages.

The object of the invention is to provide 10 a gage which will register the height of a liquid in a tank at some distant point.

A further object of the invention is to provide a gage for the purpose specified which is controlled by a source of electricity and associated circuits.

A further object of the invention is to provide a device of the type and for the purposes specified wherein arcing or sparking due to making or breaking contact in 20 an electric circuit is eliminated thereby enabling the use of the device with tanks or receptacles containing highly volatile and explosive liquids.

A further object of the invention is to 25 provide a gage of the type and for the purposes specified, which is simple in structure, efficient in operation, and economical to manufacture.

Further objects of the invention will appear more fully hereinafter.

The invention consists substantially in the construction, combination, location and relative arrangement of parts, all as will be more fully hereinafter set forth, as shown 35 in the accompanying drawings, and finally pointed out in the appended claims.

Referring to the drawings, and to the several views appearing therein,—

Figure 1 is a view in side elevation of a 40 motor vehicle, showing one application of a gage embodying my invention.

Fig. 2 is a diagrammatic view of a wiring diagram as employed in connection with my invention.

45 Fig. 3 is a top plan view of a gage.

Fig. 4 is a view in section taken on the line 4, 4, Fig. 3, and looking in the direction of the arrows.

50 Fig. 5 is a sectional view taken on the line 5, 5, Fig. 4, and looking in the direction of the arrows.

Fig. 6 is a view in elevation and in ver-

tical section of the gage employed at the point distant from the tank or receptacle.

Fig. 7 is a sectional view of the same 55 taken on the line 7, 7, Fig. 6, and looking in the direction of the arrows.

Fig. 8 is a similar view taken on the line 8, 8, Fig. 6, and looking in the direction of the arrows.

Fig. 9 is a similar view taken on the line 9, 9, Fig. 6, and looking in the direction of the arrows.

The same part is designated by the same reference numeral wherever it occurs 65 throughout the several views.

It is among the special purposes of my present invention to provide a distant gage controlled by electric circuits and a float on the top of the liquid in the tank but 70 wherein the circuits are not made and broken within the tank, and wherein all danger due to sparks caused by the making and breaking of the respective circuits is entirely eliminated.

In accordance with my invention I provide a frame with vertical portions 1 held together by means of spiders 2, 3, at the top and bottom thereof. The frame is adapted to be inserted into the tank containing the liquid, such as the gasoline tank 4, of Fig. 1, and is provided at its top with a gage as will be hereinafter described. The vertical portions 1 of the frame form guides, for a float 5, on which float is mounted a horizontal shaft 6, suitably journaled in brackets 7, 8, carried by the floats. On the respective ends of the shaft 6 are mounted to rotate therewith gear wheels 9, 10, respectively. Suitably journaled in the 90 spiders 2 and 3, and extending the vertical length of the frame is a rack 11. The teeth 12 thereof mesh with the teeth of the gear wheel 9, as shown in dotted lines, Fig. 4. A shaft 13, preferably angular in cross section, extends the vertical length of the frame, and is journaled in the spider 3 at its lower end and extends through the center of the float 5, and through the top spider 2, as shown. Loosely mounted on the shaft 13, to allow vertical movement therealong, and to cause the rotation thereof, is a sleeve 15 provided at its upper end with a gear wheel 16 which meshes with the gear wheel

10 on the shaft 6. The sleeve 15 passes through the approximate center of the float 5, and a bearing sleeve 17 positioned between the same and the float 5, permits the 5 rotation thereof relative to the float.

From the foregoing it will be seen that when the float 5 rises or falls, according to the rise or drop of the level of the liquid in the tank, on which the float rests, the shaft 10 6, due to the movement of the float and the actuation thereof secured by the gear wheel 9 traveling up and down the rack 11, will cause the gear wheel 10 to rotate the gear wheel 16, and sleeve 15, and consequently 15 the shaft 13, in one direction or the other according to the direction of movement of the float 5, as is clearly shown.

As has been hereinbefore stated, the shaft 13 projects through the top spider 2 and 20 has mounted on its end, horizontally relative thereto, a permanent bar magnet 18 so mounted as to rotate therewith. A suitable air tight cap or cover secured to the spider 2, incloses the magnet 18 and in effect in 25 conjunction with the body portion 19 of the gage, which is also secured to the frame, makes the entire structure air-tight relative to the exterior, and, especially, to the interior of the body portion of the gage. I show one 30 simple arrangement for making the cap or cover for the frame air tight wherein I clamp a plate 20 thereover and secure it thereto by means of screws as shown.

In practice I employ a round top or cover 35 of thin material, such as thin sheet brass or other non-magnetic material, the thinnest portion of which, indicated at 21, is directly opposite and closely adjacent to the poles of the magnet 18, so that the magnet 18 40 will be free to rotate within the cap or cover, but the distance between its poles and the wall 21 of the cap or cover will be very small, but at all times substantially equal.

Secured to the body 19 of the gage is a 45 spider 22, the center of which forms a guide journal for a pin 23. The lower end of the pin 23 is pointed, as shown, and rests on the plate 20. Secured to and suspended from the lower end of the pin 23 is a horse shoe 50 magnet 24, the legs or poles of which are bent or formed to lie in close proximity to the thin wall 21 of the cap or cover, directly 55 opposite to the poles of the bar magnet 18, as shown. The upper end of the pin 23 has secured to it a pointer 25, adapted to revolve horizontally over a scale member or plate 26 suitably secured to the top surface of the spider 22. If desired, and as shown, the body of the gage may be inclosed by any 60 suitable casing, such as shown at 28, over which may be screwed a cap or cover 29, provided with the usual window of glass 30.

Loosely mounted on the shaft 23 is a commutator 31 which is held in place by a disk 65 32, secured to the shaft 23 and provided

with an upwardly extending pin 33, passing through a circular slot 34, in the surface of the commutator 31, as shown.

This arrangement affords a lost motion connection between the spindle 23 and the 70 commutator which compensates for a certain amount of vertical movement of the float 5, due to the wash of the liquid caused by vibration or other disturbances to the tank in which it is contained, without affecting 75 the rotation of the commutator 31.

Suitably secured to the body 19 of the gage, at equally spaced intervals, are electrical contacts 36, normally out of contact with the commutator 31, but adapted to be 80 placed in contact therewith through the contact element 37, which is secured to the commutator 31, to rotate therewith. Each of the contacts 36 is provided with an independent wire 38, and a wire 39, connected 85 with a brush 40, which is maintained in bearing contact with the commutator 38, may be inclosed in any suitable tubing 41, as shown in Fig. 1.

Each individual contact 36 is connected by 90 its wire 38 to a corresponding contact 43, inclosed in the casing 44, of the distant indicator dial. The contacts 43 are arranged around and in contact with a rotary commutator 45, which is provided in its surface 95 with a longitudinally extending insulation strip 46, for a purpose to be hereinafter described. The shaft 47 of the commutator 45 has mounted thereon a wheel 48, with ratchet teeth and a yoke 49 carried by suitable guides 50 and provided with teeth 51, on opposite sides of the ratchet wheel adapted to engage the teeth thereof and secure positive counter-clockwise rotation of the ratchet wheel for horizontal movement of 100 the yoke in either direction. For example, and referring particularly to Fig. 8, if the yoke 49 is moved toward the right, the lower tooth 51 forces the ratchet wheel 48 counter clockwise, and if the yoke is moved toward 110 the left the upper tooth 51, forces the ratchet wheel in the same direction. To actuate the yoke I provide an arm 55 as shown best in Figs. 6 and 7, secured thereto, which arm is attached to cores 56, operating in suitable 115 solenoids 57. The arm 55 is provided with a contact point 58, held normally in position between two terminals 59, 60, and normally pressed outwardly therebetween by means of a spring 61 acting upon the core 56 120 to which is secured the arm 55. The shaft 47 is provided with the pointer 62, adapted to read on the scale 63 through the opening 64, and the glass cover 65 in the usual manner.

The operation of the device is very simple, 125 and to more clearly describe the same reference is made particularly to Fig. 2 of the drawing which diagrammatically illustrates the wiring of the device, and wherein 70 designates generally the device shown in 130

Fig. 4, namely, the arrangement located at the tank 4, and 71, designates generally the gage hereinbefore described located at the distant point. The brush 40, commutator 31, the contacts 36, and the contacting element 37 of the commutator, are all illustrated in the device 70, and the commutator 45, insulating strip 46, contacts 43, shaft 47, ratchet wheel 48, yoke 49, and coil 57, cores 56, and the terminals 59, 60, and the contactor 58, are all illustrated in the device 71.

Assuming that the tank is full of liquid, and the pointer of the device 71 registers "Full" on the scale member 63, then when, say one gallon of the liquid is used or withdrawn the gear wheel 9, rolling down the rack 11, rotates the shaft 6, gear wheels 10, 16, shaft 13, bar magnet 18, and consequently horse shoe magnet 24, shaft 23, disk 32, and commutator 31, all as has hereinbefore been described. The commutator 31, on rotation brings the contactor 37 in contact with the terminal of one of the wires 38, say number 75. Circuit is then established from any suitable source, say the battery 76, through wire 39 to the brush 40, commutator 31, contact element 37, terminal 75, wire 77, to one of the contacts 43 of the commutator 45, in this instance, the contact 78, through commutator 45, to brush 79, wire 80, through solenoid 57, contacts 59, 58 and 60, and back to the source 76. It will be seen that this energizes the solenoid 57, thereby drawing the core 56, and consequently the yoke 49 into the same thereby securing the rotation of the ratchet wheel. When the core 56 is drawn into the solenoid 57, the contact 58 is drawn from between the terminals 59, 60, thereby breaking the circuit of the battery 76, and the spring 61, (see Fig. 6), thereupon forces the core 56 out of the solenoid 57, causing the ratchet wheels to again be partially rotated in the same direction by the teeth 51, of the yoke 49, as has been described, in connection with Fig. 8. It will be seen that this action again closes the circuit of the battery 76, at the terminals 59, 60, again energizes the solenoid 57 and keeps up this action thereby rotating the ratchet wheel 48, the shaft 47, and the commutator 45, until the insulation strip 46 comes under the contact 78, thereby breaking the circuit and maintaining the circuit broken as long as the contact 37 remains in contact with the contact 75, and until the contact 37 comes in contact with the next contact, say 81, or in other words, as long as the liquid contained in the tank remains at substantially the same level.

It is obvious that as many readings may be secured or as many graduations of the contents of the tank may be employed as desired, depending entirely on the number of contacts 43, 36, and wires 38, are em-

ployed one of each of the contacts and one wire being necessary for each reading or graduation for the scale. In other words the height of the liquid in the tank 4 will determine the displacement of the commutator 31, or rather, of the contact member 37, thereof, and the coöperation of said contact member 37 with one or another of the contacts 36, controls the circuit of the solenoid 57, which correspondingly operates to relatively displace the scale and the pointer members 62, 63. In this manner the scale and pointer devices of the indicator 44 follow the rotative displacements of the drag element 24, 18, of the magnet system and this displacement is controlled by the height or level of the fluid contained in tank 4. It will be observed that the consumption of current required is very slight, and continues only until the active contact 43, of the indicator mechanism is brought to bear upon the insulating strip 46, and while being brought into this position, the circuit is maintained closed intermittently through the action of the solenoids in effecting the make and break of the circuit through contacts 58, 59 and 60.

It will thus be seen that I have provided a simple and efficient electrically operated device for reading the level of liquids in a tank at a distant point, which is especially adapted for use in connection with volatile, explosive liquids, and wherein all danger of ignition due to sparking of the contacts is entirely eliminated, as the contacts are at all times effectively air sealed from the contents of the tank.

While I have shown and described specific structures embodying my invention, it will be understood that many changes and variations in details will readily occur to those skilled in the art without departing from the broad scope of my invention as defined in the claims.

Therefore, what I claim as new and useful and of my own invention, and desire to secure by Letters Patent is,—

1. In a liquid indicating device an air sealed liquid container, a magnet system including a pair of relatively displaceable members, said members being respectively located inside and outside of said container, means controlled by the level of the liquid to be indicated for displacing one of said members, an electrically operated indicating device, circuits therefor, a commutator for controlling said circuits, and connections between said commutator and the other of said members.

2. In a liquid indicating device, an air sealed liquid container, a magnet system including a pair of relatively displaceable members, said members being respectively located inside and outside of said container, means controlled by the level

of the liquid to be indicated for displacing one of said members, an electrically operated indicating device, circuits therefor, a commutator for controlling said circuits, and lost motion connections between said commutator and the other of said members.

3. In a liquid indicating device, an air sealed liquid container, a magnet system including relatively displaceable members, said members being respectively located inside and outside of said container, means controlled by the level of the liquid to be indicated for relatively displacing one of said members, and an electrically actuated indicating device controlled by the coöperating displacement of the other of said members, and means for sealing said magnet system from the container of said liquid.
- 10 4. In a liquid indicating mechanism for vehicles, an indicating device located at the front end of the vehicle, a fluid receptacle located at a distance therefrom, electrical devices for operating said indicating device, circuits therefor, contacts for controlling said circuits, means controlled by the level of the liquid in said receptacle for controlling said contacts, and means for completely sealing said contacts from said receptacle.
- 15 5. In a liquid indicating mechanism for vehicles, an indicating device located at the front end of the vehicle, a fluid receptacle located at a distance therefrom, electrical devices for operating said indicating device, circuits therefor, a second indicating device, means for operating the same, means controlled by the level of the liquid to be indicated for controlling said circuits, and
- 20 6. In a liquid indicating mechanism for vehicles, an indicating device located at the front end of the vehicle, a fluid receptacle located at a distance therefrom, electrical devices for operating said indicating device,
- 25
- 30
- 35
- 40
- 45

circuits therefor, a second indicating device, including a scale and displaceable pointer member, magnetic devices controlled by the level of the liquid to be indicated for displacing said pointer member and means for automatically opening the circuit of said electrical devices when said pointer member attains a displaced position corresponding to the level of the liquid.

7. In a liquid indicating mechanism for vehicles, an indicating device located at the front end of the vehicle, a fluid receptacle located at a distance therefrom, electrical devices for operating said indicating device, circuits therefor, a second indicating device, including a scale and displaceable pointer member, magnetic devices controlled by the level of the liquid to be indicated for displacing said pointer member and means for automatically opening the circuit of said devices when said pointer member attains a displaced position corresponding to the level of the liquid and means for intermittently opening and closing the circuit of said electrical devices to effect the displacement of said pointer member.

8. In a liquid indicating mechanism for vehicles, an indicating device located at the front end of the vehicle, a fluid receptacle located at a distance therefrom, electrical devices for operating said indicating device, circuits therefor, a second indicating device, including a scale and displaceable pointer member, magnetic devices controlled by the level of the liquid to be indicated for displacing said pointer member and means for automatically opening the circuit of said electrical devices when said pointer member attains a displaced position corresponding to the level of the liquid, said means controlled by the movement of said pointer member.

In testimony whereof I have hereunto set my hand on this 21st day of February, A. D. 1916.

TETSUSHIRO NAKAMIGAWA.
